Letters Patent No 1364 Dated Dec 18 1860

The schedule referred to in these Letters Patent is making part of the same.

Des 1364

To all whom it may concern:

Be it known, that W^l. A. S. Vedder, of the City of Troy, in the County of Rensselaer, and State of New York, and Ezra Ripley, of the same place, have jointly invented or produced a new and original Design for Box-Stone Plates, and we do hereby declare that the following is a full and exact description of the same, reference being had to the annexed photographic drawing, which makes a part of this specification.

Our new ornamental design for box-stone plates consists of the four compound ornaments $\text{U}, \text{U}, \text{U}, \text{U}$, arranged in the corners, and the raised compound ornament $\text{m}, \text{m}, \text{m}$, in the middle of a central depressed portion, of an oblong panel in the plate, so that the whole presents the appearance represented by the annexed photographic drawing.

What we claim as new, of our invention or production and desire to secure by Letters Patent, is:—

The ornamental design for box-stone plates herein described.
